UNITED STATES PATENT OFFICE

JOSEPH SANSONE, OF JERSEY CITY, NEW JERSEY

PERMANENTLY ATTACHED COLLAR BUTTON

Application filed April 16, 1931. Serial No. 530,486.

This invention relates to new and useful improvements in permanently attached collar buttons.

The invention has for an object the provision of a device of the class mentioned which is of simple durable construction, dependable in use and efficient in action, and which can be manufactured and sold at a reasonable cost.

10 The invention proposes a permanent button support collar band or the like comprising a band, a plurality of button holes formed in the band, collar buttons supported in said button holes, means for permanently securing said collar buttons in the button holes, and means in the band for temporarily locking said collar buttons in place.

At the present time support bands are in use which have detachable buttons for insertion in button holes therein. These bands have many disadvantages, among which are the following. In case the button holes are too wide the bases of the collar buttons become easily disengaged therefrom and fall out of place. As the buttons are so small, they are easily lost and discomfort usually ensues. Furthermore, especially in evening dress shirts, the starch used in laundering them causes the button holes to become sealed and this also results in great discomfort in that it is necessary to first part the button holes for permitting the insertion of the collar buttons.

The instant invention proposes to do away with these evils in view of the fact that the collar buttons are always permanently attached to the collar band. In this way the collar buttons cannot fall out of place nor can the starch used in washing the shirts seal the button holes. Furthermore, dressing usually accomplish in haste and when the button is detached fumbling usually results. This is eliminated by the instant device in view of the fact that the button is always in place and the collar need only be snapped on.

For further comprehension of the invention, and of the objects and advantages thereof, reference will be had to the following description and accompanying drawing, and to the appended claims in which the various

novel features of the invention are more particularly set forth.

In the accompanying drawing forming a material part of this disclosure:

Fig. 1 is a perspective view of a support 55 collar band with buttons attached.

Fig. 2 is a vertical cross section taken on the line 2—2 of Fig. 1.

Fig. 3 is an elevational view taken on the line 3—3 of Fig. 1.

Fig. 4 is a vertical cross section of Fig. 3 taken on the line 4—4.

Fig. 5 is an enlarged view similar to the front portion of Fig. 1, but showing the modification thereof.

Fig. 6 is a vertical cross section of Fig. 5 taken on the line 6—6.

Fig. 7 is a view similar to Fig. 3 showing a modification thereof.

The permanent button support collar band 70 or the like consists of a band 10, a plurality of button holes 11 formed in the band, collar buttons 12 supported in said button holes, and means for permanently securing the collar buttons in the button holes.

The band 10 consists of a front facing 13 and rear material 14. The collar support band is shown attached on the shirt material 14 in Fig. 1. Though illustrated in Fig. 1 as attached on the neck portion of the shirt, the device could also be attached on the cuffs or the openable front of the shirt. The band is illustrated in an open position with the collar button and the receiving button hole detached.

The button holes 11 are shown on each end of the separated collar band and extend through both the front and rear facings of the band. The button hole at the rear of the collar band is only cut in the facing material 13 of the band and does not extend through the rear material 14. A rear pocket 15 is formed by stitching the front facing 13 and the rear material 14 together at substantial distances from the button hole. The front pocket 17 is formed by sewing the reinforcing member to the rear material 14 of the band at 18. This reinforcing material is circular and the stitches are at a substantial distance from the button hole.

Customary collar buttons are placed in these button holes. These collar buttons 12 have base portions 19, shank portions 20 and head portions 21. The rear collar button has a head portion 21 pivotally mounted at 22 to the base portion 19. Stitches 23 are sewed between the materials of the band and directly around the circumference of the base portions 19 of the collar buttons so that the collar buttons are prevented from movement. After the collar buttons have been inserted in the button holes and sewed in place, the pockets 15 and 17 are sewed closed.

In the modified form of the device illustrated in Figs. 5 and 6, an adjustable means for temporarily locking the collar button in place is shown. Flat semi-flexible member 24 preferably made of whalebone is inserted in the pocket. This member is sewed in place by stitches 25 and is formed with a cutout portion 26 on one edge. The cutout portion 26 has a width to engage the shank portion of the collar button. In the front pocket, member 24 is inserted around the shank 20 of the collar button, the pocket is closed and thread 25 is sewed so as to hold the member 24 in place. Since the length of the button hole 11 is reduced by means of the member 24, the collar button cannot be removed.

Numeral 27 indicates the inoperative position of the member 24, and 28 indicates the operative position of the member 24 around the collar button and directly in back of the button hole. If it is desired to remove the collar button, it is merely necessary to break the stitches 25, then slide the member 24 to the inoperative position 27 and thereby open the button hole aperture 11.

Fig. 7 indicates a modification of the rear portion of the collar band and is similar to the modification shown in Fig. 5. Two members 24 are inserted opposite each other and are inoperative when in position 29. In order to make these members operative they are moved toward each other so as to have the portions around the cutout 26 overlapping each other. They are then sewed in place by stitches 25. In this position the collar button is prevented from detachment. In order to release the collar button, it is only necessary to break the threads 25 and slide the members 24 back into the inoperative positions 29.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

1. A permanent button support collar band

or the like comprising a band, a plurality of button holes formed in the band, collar buttons supported in said button holes, and adjustable means for locking said collar buttons in place, said means including a flat semi-flexible member formed with a plurality of apertures and a cutout portion on one edge, said cutout portion of a width for substantially accommodating the shank of the collar button, said member being disposed between the front facing and rear material of the collar band and directly behind the button hole and around the shank of the collar button to prevent removal of same.

2. A permanent button support collar band or the like comprising a band, a plurality of button holes formed in the band, collar buttons supported in said button holes, and adjustable means for locking said collar buttons in place, comprising a pair of semi-flexible members disposed between the front facing and rear material of the collar band directly behind the button hole and capable of being so positioned as to have overlapping edges, cutout portions on the overlapping edges of each member and of a width for substantially accommodating the shank of the collar button and so as to form an aperture, and means for securing said members to the collar band.

3. A permanent button support collar band or the like comprising a band, a plurality of button holes formed in the band, collar buttons supported in said button holes, and adjustable means for locking said collar buttons in place, comprising a pair of semi-flexible members disposed between the front facing and rear material of the collar band directly behind the button hole and capable of being so positioned as to have overlapping edges, cutout portions on the overlapping edges of each member and of a width for substantially accommodating the shank of the collar button and so as to form an aperture, and means for securing said members to the collar band, comprising apertures formed in the members, and stitches engaging between the apertures and the band.

4. A permanent button support collar band or the like comprising a band, a plurality of button holes formed in the band, collar buttons supported in said button holes, and adjustable means for locking said collar buttons in place, comprising a pair of semi-flexible members disposed between the front facing and rear material of the collar band directly behind the button hole and capable of being so positioned as to have overlapping edges, and cutout portions on the overlapping edges of each member and of a width for substantially accommodating the shank of the collar button and so as to form an aperture.

5. A permanent button support collar band or the like comprising a band, a plurality of

button holes formed in the band, collar buttons supported in said button holes, and adjustable means for locking said collar buttons in place, comprising a pair of semi-flexible members disposed between the front facing and rear material of the collar band directly behind the button hole and capable of being so positioned as to have overlapping edges, cutout portions on the overlapping edges of each member and of a width for substantially accommodating the shank of the collar button and so as to form an aperture, and means for securing said members to the collar band, comprising apertures formed in the members, and means engaging between the apertures and the band.

In testimony whereof I have affixed my signature.

JOSEPH SANSONE.
